Silvers, et al., U.S. Appl. No. 14/085,759, filed Nov. 20, 2013, titled Projectile-Weapon Reticle with Holdover Aiming Features for Multiple Projectile Velocities.

(Continued)

Primary Examiner — Michael A Pratt(74) *Attorney, Agent, or Firm* — Stoel Rives LLP; Robert R. Teel(57) **CLAIM**

We claim the ornamental design for a reticle for a riflescope or other projectile-weapon aiming device, as shown and described.

DESCRIPTION

FIG. 1 is a view of a reticle for a riflescope or other projectile-weapon aiming device, as viewed at low magnification through an eyepiece end of a riflescope, according to a first embodiment;

FIG. 2 is a view of the reticle of FIG. 1, as viewed at high magnification through an eyepiece end of a riflescope;

FIG. 3 is a view of a reticle for a riflescope or other projectile-weapon aiming device, as viewed at low magnification through an eyepiece end of a riflescope, according to a second embodiment;

FIG. 4 is a view of the reticle of FIG. 3, as viewed at high magnification through an eyepiece end of a riflescope; and, FIG. 5 is an isometric view of an environment of use for the reticles of FIGS. 1–4.

In FIGS. 1–5, the broken lines indicate environmental features that form no part of the claimed design. Specifically, in FIGS. 1–4, the tortoise (or turtle) and hare (or rabbit) indicia in broken lines form no part of the claimed design. In FIGS. 3 and 4, the “YDS” letters and upper left and upper right aiming marks in broken lines form no part of the claimed design.

1 Claim, 5 Drawing Sheets(56)
